United States Patent Office.

JOHN H. LA BAU, OF BROOKLYN, NEW YORK.

Letters Patent No. 91,753, dated June 22, 1869.

IMPROVEMENT IN STRIKING-MOVEMENT FOR CLOCKS.

The Schedule referred to in these Letters Patent and making part of the same.

To all whom it may concern:

Be it known that I, JOHN H. LA BAU, of Brooklyn, in the county of Kings, and State of New York, have invented a new and improved Striking-Movement for Clocks; and I do hereby declare that the following is a full, clear, and exact description of the same, reference being had to the accompanying drawings, forming a part of this specification.

My invention consists in a novel striking-movement for clocks, whereby the time of day is acoustically indicated at as many regular intervals during every hour as may be desired, and the hearer may know, by such indication, the exact time without any knowledge of the previous striking, the striking of the hours being repeated with the striking of the intervening intervals.

To enable those skilled in the art to make and use my invention, I will proceed to describe it with reference to the drawings, in which is represented that manner I have selected as best suited for carrying out my invention.

Figure 1 represents a side view of my improved striking-movement for clocks;

Figure 2 represents an edgewise sectional view of the same, taken through a line passing vertically through its centre;

Figure 3 represents a reversed view of fig. 1, with intervening plate removed; and

Figure 4 represents, in detail, a sectional view of a portion of the movement thereof.

Similar letters of reference indicate corresponding parts in the several figures.

A is a centre spur-wheel, carried upon a spindle, a, and driven by a spur-wheel, B, which in turn is driven by a main-spring, B'.

The said centre-wheel A is regulated in its motion by means of a train of gearing, C, terminating in a fan or fly-wheel, C'.

Said train C is started and checked by the tripping and falling of a combination of levers, D, operating upon a notched or mutilated disk, D', carried upon the spindle of one of the gearing-wheels of the said train, substantially after the manner of starting and checking of the striking-movement of the ordinary clock.

Said tripping of the levers D is produced by means of a ratchet, b, carried upon an extended termination, b', of the minute-hand spindle of the clock.

Upon the outer or near surface of the wheel A, near its outer edge, are arranged fixed studs or pins d, having their points driven into the wheel, or attached thereto in any suitable manner, with their outer ends projecting outwardly from the surface thereof.

Said pins d are arranged upon the wheel in suitable groups, comprising different numbers of pins.

The arrangement of the pins in the groups is pref-

erably that represented in the drawing, but may be of any arrangement for producing such signals as are best calculated to impart a correct knowledge of the time of day to the hearer.

These groups, as represented in the drawing, are twelve (12) in number, but may be of any desirable number for designating the intervals or subdivisions of the hour, and are equidistantly arranged around the wheel, so that by the rotation of the wheel, the said groups will each, in turn, be brought against or in contact with the points of suitably-arranged music-box reeds f, in such manner as to produce sounds and combinations of sounds thereby.

Said reeds constitute, preferably, six (6) in number, each varying in tone, in regular order, from one side to the other of the group thereof, so that the groups of pins d, according to their arrangements, will strike or sound, in succession, any number of said reeds corresponding with the particular time it is intended to designate, beginning at the deeper tones and ascending to the higher ones for the first half hour, and reversing the order for the last half hour, but may be of any arrangement for producing such signals as is best calculated to impart a correct knowledge of the time of day to the hearer.

Upon the opposite side of the wheel A, and at equal distances apart, is also arranged a series of fixed pins or studs, e, corresponding in number with the number of groups formed by the pins d.

These pins e also have their points driven into the wheel A, in the same manner as the pins d, or otherwise suitably attached, with their opposite ends projecting outwardly from the surface of said wheel, so that said pins e, by the rotation of the wheel A, will engage with the upper extremity of a vertical lever, g, of a rock-shaft, G, so as to cause the rocking of the said shaft by the lateral movement and release of said lever g, simultaneously with or immediately after the sounding of the reeds f by the pins d, for a purpose hereinafter explained.

The rock-shaft G has one of its extremities to pass through the frame, and is supported within a bearing provided in a bracket, H, secured upon the outside of the plate.

Near the outer extremity of the shaft G, and passing transversely through it, is a lever, h.

Said lever h is or may be provided with a screw-thread, cut upon that portion which passes through the shaft, for its more effectual retention therein, and also to provide for its longitudinal adjustment when desirable.

Upon the outer portion of the spindle a, outside of the frame, is carried a spur-wheel, A'.

Said wheel A' is constructed, preferably, of a uniform size with the wheel A, and is fitted to turn loose-

ly upon said spindle *a*, and derives its motion by connection therewith of a ribbon-spring, *i*, while its motion is regulated by a train of gearing, *I*.

Said spring *i* is connected, by its outer end, to the wheel *A'*, and, by its inner end, to the hub of a spur-wheel, *j*, so that the turning of said wheel *j* will cause the turning of said wheel *A'*, or the winding of the spring *i*.

Said wheel *j* is fitted to turn loosely upon the hub of the wheel *A'*, and is rotated by a pinion, *k*, projecting through an opening in the plate.

Said pinion *k* is secured upon the spindle of a spur-wheel, *j'*, arranged upon the opposite side of the intervening plate, and which gears with and is driven by a pinion, *k'*, carried upon the spindle *a*.

The spur-wheels *j j'*, and their respective pinions *k k'*, are so proportioned that one revolution of the spindle *a* will produce one-twelfth ($\frac{1}{12}$) part of a revolution of the wheel *j*, which will cause the same degree of rotation of the wheel *A'*, or a corresponding degree of tension of the ribbon-spring *i*, when the wheel *A'* is prevented from turning.

Upon the inner or rear surface of this wheel *A'*, and near its outer edge, are arranged, at equal distances apart, twelve (12) fixed studs or pins *o*, corresponding with the hours of the day.

Said pins *o* are driven into the wheel *A'*, or otherwise attached thereto, in the same manner as pins *d* and *e* are attached to the wheel *A*.

The wheel *A'* is prevented from turning, when the spring *i* is being wound, by means of the engagement of said pins *o* with an inwardly-bent end of a sliding latch, *l*.

Said latch *l*, the formation of which is best understood by reference to fig. 4, in the drawing, is carried in a lever, *m*, of suitable form and construction thereto, as also illustrated in same figure.

Said latch *l* is susceptible of a longitudinal-sliding movement, in or through said pivoted lever, for a purpose hereinafter explained.

The lever or arm *m* is pivoted upon the outer extremity of the spindle *a*, immediately in front of the wheel *A'*, so that the bent or angular portion *l* of the latch *l*, will clear the periphery of the wheel during the lifting of the lever or turning of the wheel.

Projecting in an outward direction from the outer extremity of the said arm or lever *m*, and passing through an opening in the bended portion *l* of the sliding latch *l*, is a fixed stud, *n*, around which is coiled a spiral spring, *c*, and secured thereon by means of a nut, *n'*.

The inner extremity of this spiral spring *c* acts against the angular portion *l* of the sliding latch *l*, in such manner as to keep its inwardly-bent extremity in position for engaging with any one of the pins *o*.

The arm or lever *m* is connected with the lever *h* of the rock-shaft *G*, by means of a connecting-rod, *p*, so that the rocking of said shaft, produced by the action of the pins *e* against the vertical lever *g*, causes the raising of the outer extremity of the pivoted arm or lever *m*, which causes, by means of the engagement of the latch *l* with some one of the pins *o*, the backward turning of the wheel *A'*, said turning of the wheel *A'* being made in a direction contrary to or against the action of the ribbon-spring *i*, so that upon the release of the lever *g*, from contact with the pin *e*, the said spring *i* will carry the wheel *A'* back to its original position, where it is checked by contact of the lever *m* with any suitable impediment, which may, if desired, be provided with a means of adjustment for varying the checking-point, as shown by the screw *r*, in fig. 1.

Upon the outer surface of the wheel *A'*, and near the edge thereof, are provided fixed pins *s s'*, arranged in suitable groups, and having their outer ends projecting outwardly, for a purpose hereinafter explained.

E and F are clock-bells of ordinary construction, one composed of bell-metal, or other suitable material, and the other of metal wire.

Said bells E and F are suitably arranged upon the frame, and are provided with hammers *t t'*, pivoted upon a bracket, *u*, and having suitable projections, *V V'*, for engagement therewith of the pins *s s'*, during the rotating of the wheel *A'*, so that said rotating of the wheel causes the sounding of said bells.

W is a vertical lever, pivoted, by means of a screw, *W'*, to the upper portion of the bracket *H*.

Said lever W is of a curved form at its upper extremity, as represented in fig. 1, but may be of any suitable form for effecting the purpose for which it is designed, and is provided, near its upper extremity, with a projection or tooth, 2.

This said lever W has the outer edge of its upper termination resting against the inner end of the sliding latch *l*, so that the said projection 2, by means of the action of the spiral spring *c* against the said latch, is kept in close proximity to the periphery of a disk, 3, carried upon the extremity of the spindle *a*, immediately in front of the pivoted arm or lever *m*.

The said disk 3 is provided with a projection or tooth, 4, which, at every revolution of the spindle *a*, acts against the tooth 2 of the lever W, so as to force back the said lever, together with the sliding latch *l*, thereby releasing the pin *o* and allowing the wheel *A'*, by action of the ribbon-spring *i*, to rotate one-twelfth ($\frac{1}{12}$) of a revolution, or until checked by the striking of the next succeeding pin *o* against the inwardly-bent extremity of the latch *l*.

The teeth of the ratchet *b* correspond in number with the number of groups formed by the pins *d*, which in the drawing are twelve (12), so as to cause the tripping of the levers D twelve times during each rotation of the minute-hand spindle *b*, or at intervals of every five minutes, but may be constructed for intervals of longer or shorter duration, if desirable.

The levers D are lifted by means of the said teeth of the ratchet *b*, which sets in motion the wheel *A*, by means of the main-spring B.

The rotation of said wheel *A* brings, in succession, the several groups of pins *d* against the ends of the music-box reeds *f*, in such manner as to produce sounds thereby, in accordance with the number and arrangement of the pins in each particular group, each of which is designed to indicate some one of the twelve intervals or subdivisions of the hour.

Simultaneously with said sounding of the reeds, the corresponding pin *e* engages with the upper end of the lever *g*, causing its displacement in such manner as to produce the rocking of the shaft *G*, which causes the backward turning of the outer wheel *A'* one-twelfth of a revolution, by means of levers and connecting-rods, as already described.

This backward movement of the wheel *A'* causes one of the groups of pins *s* or *s s'* to pass by the rear projections *V V'* of the bell-hammers *t t'*, which, owing to the construction of the parts, are allowed, in said backward motion, to engage therewith without sounding the bells.

The groups *s* are intended to engage with the rear projections of the hammer of the bell F during the forenoon and first half of the night, and the groups *s s'* are intended to engage with the rear projections of the hammers of both bells E and F during the afternoon and latter half of the night.

Immediately after the sounding of the reeds *f*, the lever *g* is released from the pin *e*, by means of the further rotation of the wheel *A*, and the wheel *A'*, by the action of the ribbon-spring *i*, assumes its original position, carrying the group of pins *s* or *s s'* again by the rear projections *V V'*, this time causing the bell E, if the time to be indicated be in the first half of the day or night, to be struck the required number of

strokes, and the bell F, in combination with the bell E, if the time to be indicated be the latter half of the day or night, thereby obviating the necessity of striking the full number of strokes in indicating the higher hours.

The arrangement of the parts is such that the same signals produced by the bells E, or E and F, are repeated twelve times in every hour, or once at every interval indicated or sounded upon the reeds f, by the passing of the pins d.

When the minute-hand spindle v has made one revolution, and is about starting on another hour, a portion of the wheel A, upon which there is no pin e, is brought opposite the lever g, so that said lever is not moved during that interval, but instead thereof, the tooth or spur 4, upon the disk 3, is brought against the projection 2 of the pivoted lever W, forcing back the said lever, and with it the latch l, thereby releasing the pin o from its engagement with the said latch l, and allowing the wheel A', by means of the ribbon-spring i, to rotate one-twelfth ($\frac{1}{12}$) of a revolution, or until it is checked by the hanging of the next pin o upon the latch l, which said latch will have resumed its former position, by means of the spiral spring, the pivoted lever having been released by the passing by of the tooth 4, and thus a new group of the pins s or s' is placed in position for indicating or sounding a new hour of the day upon the bells.

The rotation of the wheel A causes, by means of the gearing-wheels j j', the winding of the ribbon-spring i, the proportion of said gearing being such as

to wind the said spring to the same degree of tension at every revolution of the spindle a, from which said spring was relaxed by the forward motion of the wheel A', thereby preventing said spring from ever running down.

By this means, the hours and minutes of the day and night may be so indicated by sounds and combinations of sounds as to be ascertained as well by hearing as by sight, and, by the use of this invention, clocks may be constructed without dials or hands, the time of day being ascertained entirely by the acoustic indications produced thereby.

By the term "bell," as used in this specification, is meant any sonorous instrument or apparatus, which, upon being struck, is capable of producing sound.

What I claim as my invention, and desire to have secured by Letters Patent, is—

1. The combination of the lever m and latch l with each other, and with the pins o of the wheel A, substantially as and for the purpose herein set forth.

2. The combination of the latch l, lever W, and toothed disk 3, substantially as and for the purpose herein specified.

3. The ribbon-spring i and gearing j j', in combination with the wheels A A', for the transmission of motion from the one to the other, substantially as specified.

JOHN H. LA BAU.
